CONTAINER FOR CHROMATOGRAPHIC MATERIALS

Robert F. Leifield, Pasadena Hills, Mo., assignor to Mal-
linckrodt Chemical Works, St. Louis, Mo., a corpora-
tion of Missouri

Filed May 3, 1965, Ser. No. 85,078

Term of patent 14 years

(Cl. D58—13)

FIG.1.

FIG. 2.

FIG. 3.

FIG. 4.

FIG. 5.

FIG. 6.

FIG. 7.

FIG. 8.

FIG. 9.

FIG. 1 is a top plan view of a container for chromatographic materials embodying my new design;

FIG. 2 is a bottom plan view;

FIG. 3 is a side elevational view;

FIG. 4 is an end elevational view;

FIG. 5 is a plan view of the interior of the top portion;

FIG. 6 is a plan view of the interior of the bottom portion;

FIG. 7 is a sectional view taken on the line 7-7 of FIG. 5;

FIG. 8 is a sectional view taken on the line 8-8 of FIG. 6; and

FIG. 9 is a sectional view thereof taken on the line 9-9 of FIG. 6.

The side and end not shown are the same in appearance as the respective side and end shown in FIGS. 3 and 4.

I claim:

The ornamental design for a container for chromatographic materials, substantially as shown and described.
